UNITED STATES PATENT OFFICE.

LOUIS C. WENDLAND, OF OAKLAND, CALIFORNIA.

DESIGN FOR A RADIUS-ROD FOR VEHICLES.

58,959.

Specification for Design.

Patented Sept. 6, 1921.

Application filed April 21, 1921. Serial No. 463,401. Term of patent 7 years.

To all whom it may concern:

Be it known that I, LOUIS C. WENDLAND, a citizen of the United States, and a resident of the city of Oakland, county of Alameda, State of California, have invented a new, original, and ornamental Design for a Radius-Rod for Vehicles, of which the following is a specification, reference being had

to the accompanying drawings, forming part thereof.

The figure is a perspective view of the radius rod illustrating my new design.

I claim:

The ornamental design for a radius rod for vehicles, substantially as shown.

LOUIS C. WENDLAND.
